CRADLE

Herbert E. Spencer, 3852 Division Ave. SE,
Grand Rapids, Mich. 49508

Filed Mar. 20, 1968, Ser. No. 11,065

Term of patent 14 years

Int. Cl. D6—01

U.S. Cl. D5—5

FIG. 1 is a perspective view of a cradle showing my new design;

FIG. 2 is a side elevational view thereof;

FIG. 3 is an end elevational view thereof;

FIG. 4 is an end elevational view of one end of the "box-portion" of the cradle; and

FIG. 5 is an end elevational view of the other end of the "box-portion" of the cradle.

The side opposite to that shown in FIG. 2 is a mirror image of the side shown.

I claim:

The ornamental design for a cradle, substantially as shown and described.
